SHIRT PACKAGE AND METHOD OF MAKING
THE SAME

Ralph Adams, Macon, Ga.

Application September 23, 1949, Serial No. 117,425

13 Claims. (Cl. 206—46)

1

This invention pertains to the packaging of men's sport shirts or similar garments. Since the collars of sport shirts and the soft collar of dress shirts have little inherent stiffness, the difficulties incident to the packaging of such shirts for delivering to the retail trade are even greater than those commonly encountered in the packaging of dress shirts which have stiffly starched collars which, to a substantial degree, are shape-retaining.

In packaging shirts for shipment to the trade, it is customary to pack three shirts to the box. The stiff collar of a dress shirt offers at least some resistance to crushing, even though if unprovided with a stiffener, but soft collars are badly crushed and wrinkled if packed without stiffeners. While it has been proposed to pack shirts with the collars flat, this does not appeal to the retail trade, and has not been widely adopted.

To meet the demands of the retail trade, it is necessary that the shirt, when removed from the shipping container, shall have the smoothness and unwrinkled, crisp appearance distinctive of a new shirt as it leaves the factory laundry. It must be capable of being handled by the retailer (for example when placing it in a display case or window) without danger of unfolding, and when so displayed, any temporary stiffeners employed for preserving its shape must be invisible or at least very inconspicuous.

Usually a stiff "board" or cardboard, or the like, is arranged within the body of the shirt so as to impart temporary stiffness and to prevent the shirt from sliding about in the shipping container, and usually this board has an integral tab in its upper edge which is inserted between the front and rear plies of the collar so as to hold the rear portion, at least, of the collar in erect position. Usually a narrow collar stiffener also of cardboard or like stiff sheet material is disposed between the neckband and cape portions of the collar, this collar stiffener embracing the neckband portion of the collar and for shirts with soft collars, usually extending forwardly at each side substantially to the front opening of the shirt. This collar stiffener imparts a certain degree of resiliency to the folded collar, so that when packed, the collar resists crushing and retains its initial shape.

In dress shirts having stiff collars, the neckband and cape portions of the collar are in close contact and are difficultly separable due to their stiffness, but in shirts having soft collars the soft neckband and cape portions of the collar

2

offer but little resistance to separation. When a collar stiffener is placed between the neckband and cape portions of the collar of a dress shirt it may be depended upon to remain in place due to the stiffness of the collar and needs no fastening means to insure its retention in functional position. However, it is otherwise when a stiffener is inserted between the neckband and cape portions of a soft collar. Unless the collar stiffener be positively secured to the shirt it tends to become displaced and thus distort the soft material of the collar, or it may even drop out entirely, leaving the side portions of the collar unsupported and free to collapse or wrinkle. To avoid such an occurrence it has been proposed to pin the forward ends of the collar stiffener to the shirt front, the pins passing through the cardboard of the stiffener and being so located that they are concealed by the tips of the collar.

While pins appear to be necessary for holding some parts of the folded shirt in position during shipment and while on display, the purchaser of a new shirt must search for and remove these hidden pins before donning the shirt. This has been the cause of much complaint. For this reason, among others, shirt manufacturers have made every effort to devise ways of folding shirts so as to reduce the number of pins employed to a minimum. Thus the addition of two or more hidden pins to a soft collar shirt (in addition to the usual pins necessary to hold the shirt folded) is contrary to good practice and very undesirable. Moreover, the pinning of this stiff cardboard band to the shirt is difficult and adds to the labor cost. Even the cost of these additional pins is an item which must be considered in production cost.

The principal object of the present invention is to produce a novel shirt package comprising a shirt having a soft collar provided with a temporary stiffener and wherein the stiffener is firmly anchored in place without recourse to the use of hidden pins. A further object is to provide a novel shirt package comprising a soft collar shirt and wherein the collar stiffener is held in position by a single temporary fastener of a kind which is readily applied and which is easily accessible for removal, although inconspicuous and in fact substantially unnoticeable when the shirt is on display. A further object is to provide a novel method of making a shirt package comprising a soft collar shirt and a collar stiffener. Other and further objects and advantages of the invention will be pointed out in the following more detailed description and by

reference to the accompanying drawings wherein Fig. 1 is a plan view, with parts broken away, of a shirt having combined therewith a collar stiffening means in accordance with the present invention;

Fig. 2 is a fragmentary rear elevation of the shirt shown in Fig. 1 to larger scale;

Fig. 3 is a fragmentary diagrammatic section substantially on the line 3—3 of Fig. 2;

Fig. 4 is a fragmentary plan view of a shirt board used in packaging the shirt;

Fig. 5 is a fragmentary plan view of the collar stiffener;

Fig. 6 is a rear view, to large scale, of a fastener element of a type useful in the practice of the present invention;

Fig. 7 is an edge view of the fastener shown in Fig. 6 as it appears before application to the shirt;

Fig. 8 is a view similar to Fig. 3 but illustrating a slight modification; and

Fig. 9 is a fragmentary plan view of a shirt board employed in the construction shown in Fig. 8.

For convenience in description but without limitation, the soft-collar shirt here illustrated by way of example is a conventional sport shirt.

Referring to the drawings, the numeral 1 indicates a sport shirt folded in conventional manner for shipment. As shown, this shirt comprises the front or bosom portion 2 and the collar 3, the latter being of soft construction, that is to say it is not intended to be starched stiff, and comprising the cape portion 4 terminating in the points 5, and the neckband portions 6. Customarily in sport shirts of this type the cape and neckband portions are integral and there is no seam or other means for defining the fold line.

The numeral 7 designates a shirt board of generally conventional type, customarily made from stiff cardboard and which is introduced between the front 2 of the shirt and the folded under portions of the shirt, this board usually having an integral tab 8 having the fold line 9, this tab 8 being turned upwardly at right angles to the body of the board and being disposed between the neckband and cape portions of the shirt collar so as to hold the rear part of the collar erect.

The numeral 10 designates a collar stiffener, usually of stiff cardboard and of a width substantially equal to the height of the neckband of the collar and of a length such that when it is arranged to embrace the neckband its forward ends 11 reach nearly to the front opening of the shirt. The stiffener 10 is interposed (Fig. 3) between the upstanding tab 8 of the shirt board and the cape portion 4 of the collar.

As above noted, the soft collar of the sport shirt is so pliable that it exerts little confining action upon the stiffener 10 interposed between the neckband and cape portions of the collar so that unless some means be provided for retaining the stiffener, the latter will slip down and even escape entirely from the collar and no longer affords a proper support for holding the fold line of the collar smooth and unwrinkled and no longer supports the side portions of the collar upright when placed in the shipping box. In accordance with the present invention the stiffener 10 is temporarily secured to the shirt by means of a simple fastener or clip 12. The clip here illustrated is of the type commonly used for fastening papers together and known to the trade as an "O-K" fastener. However it is to be understood that equivalent fastening means of specifically dif-

ferent construction may be employed within the scope of the invention. The clip 12, as illustrated in Figs. 6 and 7, consists of a length of sheet metal, for example brass, bent approximately to U-shape so as to provide the legs 13 and 14 united at the bend 15. The leg 14 has a sharp pointed prong 16 struck out from its substance and the leg 13 has an opening 17 designed to receive the point of the prong 16 when the fastener is in operative position.

In using such a fastener for securing the stiffener 10 in place, the leg 14 of the fastener will be slipped up between the tab 8 and the stiffener 10, as shown in Fig. 3, until the lower registering edges of the stiffener 10 and the cape portions 4 of the collar are received within the bend 15 of the fastener. The other leg 13 of the fastener is disposed at the outside of the cape portion 4 of the collar. Pressure is now applied so as to bring the legs 13 and 14 into substantially parallel relation; in thus bending the fastener the prong 16 is projected rearwardly through the stiffener 10 and usually so that its point enters, to some extent, into the material of the cape portion 4 of the collar. Depending upon the thickness of the stiffener and collar material and the length of the prong 16 the penetration of the collar material by the prong will vary all the way from no substantial penetration to a penetration such that the point of the prong reaches into the opening 17 in the leg 13 of the fastener. Since the fastener is of a material which is quite stiff and retains the shape imparted by bending it, it provides a substantial clamping action, even though the prong 16 may not enter substantially into the material of the collar, and thus grips and anchors the stiffener in position so that it cannot slip out from between the neckband and cape portions of the collar. A single fastener of this type applied substantially at the center of the rear of the collar is found amply sufficient to retain the stiffener in proper functional position. Although the rear leg 13 of the fastener is visible when the collar is observed from the viewpoint of Fig. 2, it is really inconspicuous, and almost wholly invisible when the collar is seen as it lies in the shipping container or as usually displayed in a window lying flat or inclined downwardly and forwardly toward the front of the window. On the other hand, the fastener is readily accessible and easily discoverable by a person who wishes to remove the stiffener from the shirt, since the leg 13 of the fastener is not actually concealed.

This fastener is very readily removable merely by slipping the thumbnail between the upper edge of the leg 13 and bending the leg rearwardly, thus spreading the legs 13 and 14 and disengaging the collar material from the prong 16 whereupon the stiffener together with the fastener may be withdrawn and discarded. This operation of removing the fastener is much simpler than that of searching for and removing a plurality of hidden pins; on the other hand its application to the shirt by the shirt manufacturer involves much less trouble and expense than does the use of the pins customarily employed. The penetration of the cape portion of the collar by the prong 16 is not such as to cause any damage to the collar material.

A slight modification is suggested in Figs. 8 and 9. The shirt board 7' has the collar positioning tab 8', as above described, but at the junction of the tab 8' and the board proper there is provided a slot 18. In assembling the parts (Fig. 8)

the leg 14 of the fastener 12 is passed up through this slot 18 so that it lies forwardly of the tab 8' when the latter is disposed within the collar. The leg 13 of the fastener lies to the rear of the cape portion of the collar in the same way as above described. When the legs 13 and 14 are pressed together the prong 16 of the fastener passes through the substance of the tab 8' and then through the stiffener 10 and to a greater or lesser distance into the cape portion of the collar. With this arrangement the stiffener is anchored both to the shirt board and to the cape portion of the collar. This anchorage of the parts assists in holding the collar in the desired upright position, and by uniting the parts 8' and 10, affords greater stiffness at the back of the collar than results when the tab 8' and stiffener 10 are wholly independent and unconnected.

While certain embodiments of the invention have been illustrated and described by way of example, it is to be understood that the invention is broadly inclusive of any and all modifications falling within the scope of the appended claims.

I claim:

1. A shirt package comprising a soft-collar shirt having a collar which includes neckband and cape portions, a stiffener disposed between the neckband and cape portions of the collar, and a single removable fastener element temporarily uniting the stiffener directly to the cape portion of the collar.

2. A shirt package comprising a sport shirt having a collar including soft neckband and cape portions, a stiffener of sheet material interposed between the neckband and cape portions of the collar, and a single removable clamping device uniting the collar stiffener to the cape portion of the collar, said fastener being located at the rear of the collar.

3. A shirt package comprising a soft-collar shirt having a collar including soft neckband and cape portions, a stiffener of sheet material interposed between the neckband and cape portions of the collar, and a removable clip of sheet metal comprising opposed jaws between which the lower edges of the fastener and the cape portion of the collar are gripped and thereby temporarily united.

4. A shirt package comprising a sport shirt having a collar including soft neckband and cape portions, a stiffener of sheet material interposed between the neckband and cape portions of the collar, and a removable fastener having a penetrating prong which passes through the stiffener and into the cape portion of the collar, said fastener being located at the rear of the collar.

5. A shirt package comprising a soft-collar shirt having a collar including soft neckband and cape portions, a stiffener of sheet material interposed between the neckband and cape portions of the collar, the lower edge of said band being registered with the lower edge of the cape portion of the collar, and a removable clamping element of U-shape having one leg in contact with the front face of the stiffener and the other leg in contact with the rear face of the cape portion of the collar.

6. A shirt package comprising a soft-collar shirt having a collar including soft neckband and cape portions, a stiffener of sheet material interposed between the neckband and cape portions of the collar, and a removable anchoring element of U-shape having one leg interposed between the neckband portion of the collar and

the stiffener and the other leg in contact with the rear face of the cape portion of the collar, and a penetrating prong projecting rearwardly from the first-named leg of the anchoring element and into the stiffener.

7. A shirt package comprising a soft-collar shirt having a collar including soft neckband and cape portions, a stiffener of sheet material interposed between the neckband and cape portions of the collar, and an O-K fastener having the lower edges of the stiffener and cape portion of the collar disposed within its bend, the prong-carrying leg of the fastener being interposed between the neckband portion of the collar and the stiffener with the prong projecting rearwardly through the stiffener and into the cape portion of the collar, the other leg of the fastener being visible at the rear side of the cape portion of the collar.

20 8. A shirt package comprising a folded soft-collar shirt having a collar which includes neckband and cape portions, a shirt board of stiff sheet material disposed within the folded shirt, said board comprising a tab which is interposed between the neckband and cape portions of the collar at the rear of the latter, a stiffener disposed between the neckband and cape portions of the collar and which embraces the neckband, said stiffener, at the rear of the collar, being disposed between the tab and the cape portion of the collar, and a single removable fastener located at the rear of the collar and which temporarily unites the tab, stiffener and cape portions of the collar.

35 9. A shirt package comprising a folded soft-collar shirt having a collar which includes a neckband and cape portions, a shirt board of stiff sheet material disposed within the folded shirt, said board comprising a tab which is interposed between the neckband and cape portions of the collar at the rear of the latter, a stiffener disposed between the neckband and cape portions of the collar and which embraces the neckband, said stiffener, at the rear of the collar, being disposed between the tab and the cape portion of the collar, the shirt board having a slot adjacent to the junction of the tab and board proper, and a removable U-shaped fastener, one leg of which is disposed between the tab and the neckband portion of the collar, and the other leg of which is disposed at the rear side of the cape portion of the collar with the bend of the fastener embracing the edge of the slot in the shirt board, the lower edge of the fastener and the lower edge of the cape portion of the collar, said fastener having a penetrating prong which projects rearwardly through the tab and stiffener and into the cape portion of the collar, thereby to anchor the tab, stiffener and cape portion together.

50 10. That method of packaging soft-collar shirts for shipment which comprises providing a collar stiffener of sheet material designed to embrace the neckband portion of the collar and to extend around the sides substantially to the front opening of the shirt, introducing said stiffener between the neckband and cape portions of the collar, and temporarily attaching the stiffener to the cape portion of the collar at a single point at the rear of the collar.

55 11. That method of packaging sport shirts for shipment which comprises providing a collar stiffener of sheet material designed to embrace the neckband portion of the collar and to extend along the sides of the neckband substan-

tially to the front opening of the shirt, introducing said stiffener between the neckband and cape portions of the collar, and clamping the stiffener to the cape portion of the collar at the rear of the collar by means of a single removable fastener.

12. That method of packaging soft-collar shirts for shipment which comprises providing a collar stiffener of sheet material designed to embrace the neckband portion of the collar, introducing said stiffener between the neckband and cape portions of the collar, providing a U-bend clamping element, introducing the lower edges of the stiffener and cape portion of the collar into the bend of the clamping element, and closing the legs of the clamping element

15

thereby temporarily to anchor the stiffener to the cape portion of the collar.

13. That method of packaging sport shirts for shipment which comprises providing a collar stiffener of sheet material designed to embrace the neckband portion of the collar and to extend substantially to the front opening of the shirt, introducing said stiffener between the neckband and cape portions of the collar, and projecting a 5 penetrating fastener element rearwardly through the stiffener and into the cape portion of the collar thereby to anchor the stiffener to the collar.

RALPH ADAMS.
